UNITED STATES PATENT OFFICE.

BELLE M. GINGLES, OF WAUKESHA, WISCONSIN.

DARNING HORN.

Application filed March 28, 1922. Serial No. 547,432.

To all whom it may concern:

Be it known that I, BELLE M. GINGLES, a citizen of the United States, and resident of Waukesha, in the county of Waukesha and 5 State of Wisconsin, have invented certain new and useful Improvements in Darning Horns; and I do hereby declare that the following is a full, clear, and exact description thereof.

10 My invention refers to darning horns or bulbs, and it has for its primary object to provide a simple, economical and durable one piece yieldable bulb, the surface of which is unobstructed, whereby the darning 15 needle, when in use, will not be dulled by coming in contact with a hard surface, and whereby the bulb surface will cushion under pressure of the needle so as to produce a neat and symmetrical darning patch.

20 Another object of my invention is to provide a one piece rubber bulb, which serves the purpose of an ordinary horn, the bulb being provided with a neck extension, which extension at its junction with the bulb, is 25 taperedly reinforced in opposite directions to prevent undue flexure of the bulb with relation to its neck or shank.

Another object of my invention is to provide a detachable handle in connection with 30 the bulb shank having means at its opposite end for the reception of a minute yieldable rubber bulb for use in working upon smaller articles of wear.

My invention, as stated above, is particularly directed to a pliable bulb or sphere for darning, wherein the entire spherical surface is unobstructed to permit operation 35 of the needle at approximately any point within the bulb surface, except at the shank 40 extension thereof.

It is an essential feature, therefore, that the bulb shall be formed with a continuous or uninterrupted surface, for the reason that if a two piece bulb, for example, be produced for darning purposes, a broken joint or bead would necessarily occur at some point intersecting the bulb surface and the thickened bead or joint, thus developed, would defeat the object of the invention for 45 the reason that a needle operating at this thickened point would be obstructed in its passage and either dulled or broken off, should the point be imbedded into said bead. Hence in practice, such a possible construc-

tion would not perform the functions or accomplish the desired results attained in my improved structure.

With the above objects in view, the invention consists in certain peculiarities of construction and combination of parts as are 60 hereinafter set forth with reference to the accompanying illustration and subsequently claimed.

The drawing illustrates an elevation of a darning bulb embodying the features of 65 my invention, with parts broken away and other parts in section to more clearly show details of construction.

Referring by reference characters to the drawings 1 represents a rubber bulb formed 70 in elliptical or egg shape, the hollow bulb being provided with a vent 1'. The thickness of the bulb it will be noted, is a minimum at its upper or outer end and gradually increases as the lower end of the bulb 75 is approached.

It is understood that while I have exemplified an elliptical bulb, obviously the shape or dimensions may be varied indefinitely, provided the outer surface of the bulb 80 is uninterrupted and curvilinear.

One end of the bulb has extended therefrom, a hollow neck or shank 2, which neck terminates with a circular bead 2'. At the point of intersection between the walls of 85 the bulb and the neck, the rubber material is thickened, as indicated at X, and from this maximum thickened portion, the material is gradually tapered off in both directions and 90 merged into the surface of the bulb and neck respectively, to thus form a reinforced shoulder, whereby side flexure of the bulb with relation to the neck is resisted to a more or less degree, to thus prevent the bulb from buckling with relation to the handle when 95 the device is used in darning.

A handle 3 of any suitable material is provided, which handle terminates at its upper end with a crowned finger 3' that is snugly fitted into the bore of the neck. The finger 100 terminates with an annular groove 3'' for nested engagement with the bead 2' of the aforesaid neck. Hence by this rigid coupling connection, the parts are firmly held in place.

While I have preferably described a wooden handle in connection with the bulb, obviously in some instances I may mold the

2
bulb and handle in one operation from rubber material, the handle being suitably vulcanized.

The lower end of the handle 3 terminates 5 with a crowned head 4, having an annular recess 4' intersecting the same and the butt of the handle. This recess is provided for the reception of the beaded mouth 5 of a minute shell-like rubber bulb 6, which bulb 10 can be adjusted to the butt end of the handle, to be utilized for darning, for example, infants' socks, or similar small articles of wearing apparel.

Obviously I may, in some instances, 15 modify the construction of the handle 3 to such an extent that one end of it may be provided with a grooved finger or head for interchangeable adjustment thereto of bulbs of different dimensions, in which case the 20 opposite or lower end of the handle could be made in any suitable plain design.

It is to be noted that the outer end of the bulb as previously pointed out, is the thinnest portion. This portion is used for certain 25 kinds of darning where a slight give in the bulb is desirable. As the lower portion of the bulb is approached the walls become thicker as pointed out, and this offers an increased resistance to distortion by the sewing 30 needle and consequently offers, therefore, a harder surface. It is further to be noted that the socket 2 merges into the lower portion of the bulb by means of a thickened portion as indicated at X. This 35 gives, therefore, maximum strength at a point adjacent the handle and thus secures a very firm anchoring of the main body of the bulb to the handle.

A further feature is due to the peculiar 40 construction of plug 3', socket therefor, and vent hole 1'. Under certain conditions it may be desirable to maintain the air within the bulb at a slightly increased pressure

above atmospheric. This is most readily secured by the construction disclosed for when 45 the plug 3' is inserted within its socket it acts as a piston and forces air into the bulb by means of the vent 1'.

While I have shown and described one practical exemplification of my invention 50 minutely with reference to details of construction, it is understood that I may vary such structural features within the scope of the appended claims as they will hereinafter be interpreted by those skilled in the art. 55

I claim:

1. A darning horn comprising a one piece rubber bulb having a neck extending therefrom, said bulb being thinnest adjacent at its outer end and gradually increasing in 60 thickness towards the neck portion, said neck portion being of materially increased thickness and a handle fitted within said neck portion, whereby a gradually decreasing flexibility is secured from the outer portion of the bulb towards the neck portion. 65

2. A darning horn comprising a one piece bulb having a continuous uninterrupted outer surface and having a wall thickness of gradually increasing extent from its outer 70 end towards its inner end, the inner end of said bulb being of materially increased thickness and having a socket therein provided with a vent communicating with the interior of said bulb, a handle provided with 75 a plug adapted to fit into said socket and to force air from said socket through said vent and into said bulb, whereby the air pressure within said bulb may be maintained above atmospheric air pressure. 80

In testimony that I claim the foregoing I have hereunto set my hand at Milwaukee, in the county of Milwaukee and State of Wisconsin.

BELLE M. GINGLES.
